A-NOR-Steroids

Josef Fried, Princeton, and David W. Rosenthal, New Brunswick, N.J., assignors, by mesne assignments, to E. R. Squibb & Sons, Inc., New York, N.Y., a corporation of Delaware

No Drawing. Filed June 19, 1963, Ser. No. 288,920
16 Claims. (Cl. 260—468)

This invention relates to and has for its objects the provision of new physiologically active steroids, methods for preparing the same and new intermediates useful in said preparation.

The final products of this invention can be represented by the formula

wherein R'' is hydrogen; R is selected from the group consisting of hydrogen, hydroxy and acyloxy and together R and R'' is oxo ($O=$); R' is selected from the group consisting of hydrogen and acyloxy; and Z is selected from the group consisting of

wherein X is selected from the group consisting of lower alkyl (e.g., methyl) and

wherein B is selected from the group consisting of hydroxy and lower alkoxy (e.g., methoxy), and Y is iso-alkyl (e.g., iso-hexyl, iso-heptyl, iso-octyl); and

wherein W is selected from the group consisting of hydrogen, acyloxy and halogen (e.g., bromo, chloro, fluoro or iodo).

The acyl radicals preferred in the practice of this invention are those from hydrocarbon carboxylic acids of less than 10 carbon atoms, as exemplified by the lower alkanoic acids (e.g. acetic, propionic, butyric and tert-pentanoic acids), the lower alkenoic acids, the monocyclic aryl carboxylic acids (e.g. benzoic and toluic acids), the monocyclic aryl lower alkanoic acids (e.g. phenacetic and β -phenylpropionic acids), the cycloalkane carboxylic acids and the cycloalkene carboxylic acids.

(Whenever in this application and the claims appended hereto a curved line [ ] is employed in the linkage of atoms in a formula, it is meant to denote that the con-

2

nected atom may be either in the alpha or beta position as is determined in the respective compounds.)

The compounds of this invention are physiologically active steroids which possess anti-androgenic activity, i.e., they inhibit the action of androgens, and they are useful in the treatment of such conditions as hyper-androgenic acne. The compounds may be formulated for such administration, the concentration and/or dosage being based on the activity of the particular compound and the requirement of the patient.

The final products of this invention are prepared by the process of this invention which entails a number of steps beginning with compounds of the following formulae as starting material:

wherein R , R' and Z are as hereinbefore defined.

Among the starting materials which may be employed in the practice of this invention are included such triterpenoid acid derivatives as may be prepared according to the procedures disclosed in our copending application Serial No. 183,014, filed March 28, 1962, now U.S. Patent No. 3,153,038, which is a continuation-in-part of our prior application Serial No. 132,310, filed August 18, 1961, and now abandoned.

Suitable starting materials include such compounds as

- 35 3β -hydroxy-21-halo-4,4,14-trimethyl- Δ^7 -pregnene-20-one;
- 3 β -hydroxy-21-halo-4,4,14-trimethyl- Δ^8 -pregnene-20-one;
- 3 β -hydroxy-16-acetoxy-21-halo-4,4,14-trimethyl- Δ^7 -pregnene-20-one;
- 3 β -hydroxy-16-acetoxy-21-halo-4,4,14-trimethyl- Δ^8 -pregnene-20-one;
- 3 β -hydroxy-21-acetoxy-4,4,14-trimethyl- Δ^7 -pregnene-20-one;
- 3 β -hydroxy-21-acetoxy-4,4,14-trimethyl- Δ^8 -pregnene-20-one;
- 3 β -hydroxy-16,21-diacetoxy-4,4,14-trimethyl- Δ^7 -pregnene-20-one;
- 3 β -hydroxy-16,21-diacetoxy-4,4,14-trimethyl- Δ^8 -pregnene-20-one;
- 3 β -hydroxy-4,4,14-trimethyl- Δ^7 -pregnene-20-one;
- 3 β -hydroxy-4,4,14-trimethyl- Δ^8 -pregnene-20-one;
- 3 β -hydroxy-16-acetoxy- Δ^7 -eburicene-21-oate;
- Methyl-3 β -hydroxy- Δ^7 -eburicene-21-oate;
- Methyl-3 β -hydroxy- Δ^8 -eburicene-21-oate;
- Methyl-3 β -acetoxy- Δ^7 -eburicene-21-oate;
- Methyl-3 β -acetoxy- Δ^8 -eburicene-21-oate;
- Methyl-3 β -hydroxy-16-acetoxy- Δ^7 -eburicene-21-oate;
- Methyl-3 β -hydroxy-16 α -acetoxy- Δ^8 -eburicene-21-oate;
- Methyl-3 β -hydroxy- Δ^8 -lanostene-21-oate;
- Methyl-3 β -acetoxy- Δ^8 -lanostene-21-oate;
- Methyl-3 β -hydroxy- Δ^7 -lanostene-21-oate;
- 60 Δ^7 -lanostene-3 β -ol;
- Δ^8 -lanostene-3 β -ol.

In addition to the foregoing, starting materials employable in the practice of this invention may also be prepared according to the procedures set forth in copending U.S.

applications Serial No. 198,425 filed May 29, 1962, now U.S. Patent No. 3,169,957, in the names of Josef Fried and Gerald Krakower and Serial No. 212,154, filed July 24, 1962, now U.S. Patent No. 3,170,919, in the name of Josef Fried. The steps of this process are generally shown by the following equations, wherein R, R', R'' and Z are as hereinbefore defined:

In the first step of the process of this invention, the 3β-hydroxy-Δ⁸ or -Δ⁷ starting materials (Compounds A and B), enumerated hereinabove are reacted with phosphorus pentachloride to yield the respective 3-isopropyl-

idene A-nor Δ⁸-derivatives (Compounds C) and the 3-isopropylidene A-nor Δ⁷-derivatives (Compounds D). In the event that 3β-acetoxy Δ⁷- or Δ⁸-starting materials are employed in the practice of this invention, this material 5 may first be converted to the respective 3-hydroxy compounds as by treatment with alcoholic alkali metal base such as methanol potassium hydroxide.

Compounds C and D are then oxidized in the presence of a base, e.g., pyridine, to yield the respective 3-keto-A-nor-Δ⁸-derivatives (Compounds E) and 3-keto-A-nor-Δ⁷-derivatives (Compounds F) which are new compounds of this invention.

Compounds E and F are then brominated as by treatment with bromine in an acid medium to yield the 5-bromo A-nor-Δ⁸-derivatives (Compounds G) and the 5-bromo A-nor-Δ⁷-derivatives (Compounds H) which are also new compounds of this invention.

Compounds G and H are then dehydrobrominated as by treatment with a dehydrobrominating agent, such as 20 lithium bromide in dimethyl formamide medium, or collidine, to yield the 3-keto-Δ⁵(10),6,8-triene derivatives (Compounds J) which are new products of this invention.

Compounds J may then be reduced with a reducing agent, such as sodium borohydride to yield the 3-hydroxy-A-nor-Δ⁵(10),6,8-triene derivatives (Compounds K) which are also new compounds of this invention.

Compounds J may also be further reduced as by treatment with hydrogen in the presence of a catalyst, such as 30 palladium on charcoal to yield the 3-unsubstituted A-nor-Δ⁵(10),6,8-triene derivatives, which are also new products of this invention.

The invention may be further illustrated by the following examples:

35 *Example 1.—Methyl 3β-hydroxy-4,4,14-trimethyl-Δ⁷-5α-ergostene-21-oate*

A solution of 17 grams of methyl 3β-acetoxy-4,4,14-trimethyl-Δ⁷-5α-ergostene-21-oate in a mixture of 250 ml. 40 of dioxane and 250 ml. of 12% methanolic potassium hydroxide is allowed to stand at room temperature for 18 hours. The reaction mixture, which solidifies during this period of time is taken up in chloroform and water, acidified with 4 N hydrochloric acid, and the layers are 45 separated. The aqueous phase is extracted with chloroform and the combined chloroform extracts washed with water, dried over sodium sulfate and evaporated to dryness in vacuo. The resulting residue is dissolved in 250 ml. of methanol and allowed to crystallize. A first crop 50 of 12 grams and on concentration of the mother liquors a second crop of a 1 gram is obtained. The purified methyl 3β-hydroxy-4,4,14-trimethyl-Δ⁷-5α-ergostene-21-oate has the following properties: M.P. 145-148°, $[\alpha]_D^{23} +31^\circ$ (CHCl₃),

55 $\lambda_{\text{max}}^{\text{Nujol}} 3.00, 5.78\mu$

Analysis.—Calcd. for C₃₃H₅₄O₃ (486.75): C, 78.96; H, 11.18. Found: C, 78.71; H, 11.22.

60 *Example 2.—Methyl 3β-hydroxy-4,4,14-trimethyl-Δ⁸-5α-ergostene-21-oate*

Following the procedure set forth in Example 1 but substituting an equivalent amount of methyl-3β-acetoxy-4,4,14-trimethyl-Δ⁸-ergostene-21-oate for 3β-acetoxy-4,4,14-trimethyl-Δ⁷-5α-ergostene-21-oate yields methyl 3β-hydroxy-4,4,14-trimethyl-Δ⁸-5α-ergostene-21-oate.

Example 3.—4,4,14-trimethyl-Δ⁸-5α-pregnene-3β-ol-20-one

A solution of 500 mg. of 3β-acetoxy-4,4,14-trimethyl-70 Δ⁸-5α-pregnene-20-one in 100 ml. of 1 N KOH in methanol is allowed to stand at room temperature for 20 hours. The reaction mixture is neutralized with 4 N H₂SO₄, and after the addition of water the mixture is extracted with chloroform. The chloroform extract is washed with water, dried over sodium sulfate and the solvent removed 75

in vacuo. The residue (430 mg.) on recrystallization from methanol gives 390 mg. of pure 4,4,14-trimethyl- Δ^8 -5 α -pregnene-3 β -ol-20-one possessing the following properties, M.P. 253-256°; $[\alpha]_D^{23} +122^\circ$ (c. 1.2 in chloroform);

$\lambda_{\text{max}}^{\text{KBr}} 2.88\mu, 5.88\mu$

Analysis.—Calcd. for $C_{24}H_{38}O_2$ (358.54): C, 80.39; H, 10.68. Found: C, 80.39; H, 10.62.

Example 4.—4,4,14-trimethyl- Δ^7 -5 α -pregnene-3 β -ol-20-one.

Following the procedure set forth in Example 3, but substituting an equivalent amount of 3 β -acetoxy-4,4,14-trimethyl- Δ^7 -5 α -pregnene-20-one for 3 β -acetoxy-4,4,14-trimethyl- Δ^8 -5 α -pregnene-20-one, there is obtained 4,4,14-trimethyl- Δ^7 -5 α -pregnene-3 β -ol-20-one.

Example 5.—Methyl Δ^8 -lanostene-3 β -ol-21-oate

Following the procedure set forth in Example 1, but substituting an equivalent amount of methyl acetyl Δ^8 -lanostene-3 β -ol-21-oate for 3 β -acetoxy-4,4,14-trimethyl- Δ^7 -ergostene-21-oate yields methyl Δ^8 -lanostene-3 β -ol-21-oate.

Similarly, if methyl acetyl Δ^7 -lanostene-3 β -ol-21-oate is substituted in the practice of Example 5, there is obtained methyl Δ^7 -lanostene-3 β -ol-21-oate.

Example 6.—Methyl 3-isopropylidene-14-methyl-A-nor- Δ^7 -5 α -ergostene-21-oate

To a well agitated solution of 2.5 grams of methyl 3 β -hydroxy-4,4,14-trimethyl- Δ^7 -5 α -ergostene-21-oate in 350 ml. of dry toluene maintained at 0° is added 2.5 grams of phosphorus pentachloride. Immediately after the addition of the latter, a rapid stream of nitrogen is passed through the suspension and continued for 20 minutes. At this time 10% potassium carbonate solution is added to the agitated mixture and the temperature allowed to rise to room temperature. The toluene solution is washed again with sodium carbonate and water, dried over potassium carbonate and evaporated to dryness in vacuo. The residue which crystallizes spontaneously is taken up in a small amount of chloroform and diluted with methanol. Crystallization ensues furnishing 2.03 grams of the methyl - 3 - isopropylidene-14-methyl-A-nor- Δ^7 -ergostene-21-oate. The analytically pure material has the following properties: M.P. 121-121.5°, $[\alpha]_D^{23} +18^\circ$ (chf.),

$\lambda_{\text{max}}^{\text{Nuol}} 5.75\mu$

Analysis.—Calcd. for $C_{32}H_{52}O_2$: C, 81.99; H, 11.18. Found: C, 82.41; H, 11.23.

Similarly, substituting an equivalent amount of any of the 3-hydroxy- Δ^7 -starting materials set forth hereinabove on pages 3 and 4 of the specification, or which were obtained in Examples 1 to 5, for methyl 3 β -hydroxy-4,4,14-trimethyl- Δ^7 -5 α -ergostene-21-oate yields the corresponding 3 - isopropylidene - 14-methyl-A-nor- Δ^7 -derivatives thereof.

Example 7.—Methyl 3-isopropylidene-14-methyl-A-nor- Δ^8 -5 α -ergostene-21-oate

A solution of 5 grams of methyl 3 β -hydroxy-4,4,14-trimethyl- Δ^8 -5 α -ergostene-21-oate in 1000 ml. of dried redistilled toluene is treated with 5 grams of phosphorus pentachloride as described in Example 6. The reaction yields the desired methyl 3-isopropylidene-14-methyl-A-nor- Δ^8 -5 α -ergostene-21-oate in two crops amounting to 3.65 grams and 290 mg., respectively. The analytical sample is obtained by recrystallization from chloroform methanol and has the following properties: M.P. 127-128°, $[\alpha]_D^{23} +49.5^\circ$ (chf.),

$\lambda_{\text{max}}^{\text{Nuol}} 5.77\mu$

Analysis.—Calcd. for $C_{32}H_{52}O_2$: C, 81.99; H, 11.18. Found: C, 81.93; H, 11.25.

Example 8.—3-isopropylidene-A-nor- Δ^8 -5 α -pregnene-20-one

5 A solution of 100 mg. of 4,4,14-trimethyl- Δ^8 -5 α -pregnene-3 β -ol-20-one in 30 ml. of dry toluene is treated with 100 mg. PCl_5 as described in Example 6. After a total reaction time of 8 minutes the 3-isopropylidene derivative is obtained by crystallization from methanol possessing the following properties: M.P. 136-137°; $[\alpha]_D^{23} +135^\circ$ (c. 1.04 in CHCl_3);

$\lambda_{\text{max}}^{\text{KBr}} 5.85\mu$

Analysis.—Calcd. for $C_{24}H_{36}O$ (340.53): C, 84.64; H, 10.66. Found: C, 84.51; H, 10.48.

Example 9.—3-isopropylidene-21-acetoxy-A-nor- Δ^8 -5 α -pregnene-20-one

15 A solution of 100 mg. of 4,4,14-trimethyl- Δ^8 -5 α -pregnene-21-ol-20-one, 21-acetate in 20 ml. of dry toluene is reacted with PCl_5 at 0° as described in Example 6. On recrystallization from methanol there is obtained 73 mg. of the 3-isopropylidene compound of the following properties: M.P. 172-174°; $[\alpha]_D^{23} +130^\circ$ (c. 1.0 in CHCl_3);

$\lambda_{\text{max}}^{\text{KBr}} 5.69\mu, 5.79\mu$

20 *Analysis.*—Calcd. for $C_{26}H_{38}O_3$ (398.56): C, 78.35; H, 9.61. Found: C, 78.13; H, 9.37.

25 Similarly, if equivalent amounts of any of the 3-hydroxy- Δ^8 -starting materials enumerated hereinabove at pages 3 and 4 of the specification or equivalent amounts of any of the 3-hydroxy- Δ^8 -compounds obtained in Examples 1 to 5 are substituted the respective 3-isopropylidene-14-methyl-A-nor- Δ^8 -derivatives thereof are obtained.

30 *Example 10.—Methyl 14-methyl-A-nor- Δ^7 -5 α -ergostene-3-one-21-oate*

35 Through a solution of 2.5 grams of methyl 3-isopropylidene-14-methyl- Δ^7 -5 α -ergostene-21-oate and 850 mg. of pyridine (2 molar equivalents) in 125 ml. of methylene chloride which is immersed in a Dry Ice-acetone bath is passed a stream of oxygen containing 0.00129 mole of ozone/liter. When 6.1 liters of this ozone-oxygen mixture has passed through the solution, the emerging gas begins to liberate iodine from a potassium iodide trap placed after the reaction vessel and the reaction was stopped. After warming to 0° 3 ml. of glacial acetic acid and 2.5 g. of zinc dust are added with stirring permitting the reaction mixture to reach room temperature. When the ozonide is completely decomposed as indicated by testing with potassium iodide solution (approximately 1 hour) the mixture is filtered, washed thoroughly with water and the methylene chloride extract dried over sodium sulfate and evaporated to dryness in vacuo. The residue which weighs 2.6 g. is dissolved in methanol from which the desired methyl 14-methyl-A-nor- Δ^7 -5 α -ergostene-3 - one-21-oate crystallizes spontaneously. The first crop amounts to 533 mg. melting at 178-180° and a second crop (110 mg.) melts at 174-178°. The analytically pure material has the following properties: M.P. 179-181°, $[\alpha]_D^{23} -55^\circ$ (chf.),

$\lambda_{\text{max}}^{\text{KBr}} 5.75\mu$

40 *Analysis.*—Calcd. for $C_{29}H_{46}O_3$: C, 78.68; H, 10.47. Found: C, 78.94; H, 10.28.

45 Similarly, if the 3-isopropylidene-14-methyl-A-nor- Δ^7 -derivatives which may be obtained according to the procedures set forth in Example 6 are treated in accordance with the procedures of Example 10, the respective 3-keto-14-methyl-A-nor- Δ^7 -derivatives thereof are obtained.

50 *Example 11.—Methyl 14-methyl-A-nor- Δ^8 -5 α -ergostene-3-one-21-oate*

55 A solution of 900 mg. of methyl 3-isopropylidene-14-methyl-A-nor- Δ^8 -5 α -ergostene-21-oate and 300 mg. of anhydrous pyridine (2 molar equivalents) in 45 ml. of methylene chloride is ozonized at acetone-Dry Ice tem-

perature with a stream of oxygen containing 0.00129 mole/liter until KI-starch solution is blued by the existing gas. This occurs after about 2.59 liters have passed through the solution. The solution is then allowed to warm to room temperature; 1 ml. of glacial acetic acid and 600 mg. of zinc dust are added with stirring, and the mixture allowed to remain at room temperature until the ozonide is completely decomposed. The mixture is then filtered, thoroughly extracted with water, dried over sodium sulfate and the solvent removed in vacuo. The dried residue (950 mg.) is dissolved in hexane and chromatographed on a column of 40 g. of silica gel. Elution with hexane removes 80 mg. of amorphous material. Benzene (5000 ml.) elutes the pure methyl 14-methyl-A-nor- Δ^8 -5 α -ergostene-3-one-21-oate (128 mg.) which after recrystallization from methanol has the following properties: M.P. 102-103°, $[\alpha]_D^{23} +8^\circ$ (c. 0.37 in CHCl_3),

$$\lambda_{\text{max}}^{\text{KBr}} 5.75\mu$$

Analysis.—Calcd. for $\text{C}_{29}\text{H}_{46}\text{O}_3$: C, 78.68; H, 10.47. Found: C, 78.58; H, 10.45.

Example 12.—14-Methyl-A-nor- Δ^8 -5 α - and 5 β -pregnene-20-one

A solution of 192 mg. of 3-isopropylidene-A-nor- Δ^8 -5 α -pregnene-20-one and 85 mg. of anhydrous pyridine in 45 ml. of methylene chloride is ozonized as described in Example 11 until the exiting gas liberates iodine from a KI-solution. This occurs after 730 mg. of gas has passed through the solution. The solution is then allowed to reach room temperature and 0.3 ml. of glacial acetic acid and 350 mg. of zinc dust are added and the mixture kept stirring until the ozonide is completely decomposed. The mixture is then filtered, thoroughly extracted with water and the methylene chloride extract dried over sodium sulfate and evaporated to dryness in vacuo. The dried residue (190 mg.) is recrystallized from ether-hexane and furnishes the essentially pure 5 α -isomer. However, it was preferable to convert the total crude product to the better crystalline 5 β -isomer as follows: The residue (190 mg.) is dissolved in 9 ml. of methanol and to this is added 1.5 ml. of 0.7 N KOH in methanol. The mixture is allowed to stand at room temperature for 30 minutes, neutralized with glacial acetic acid and after the addition of water extracted with chloroform. The chloroform extract is washed with water, dried over sodium sulfate and evaporated to dryness in vacuo. The residue (198 mg.) on crystallization from methanol furnishes 81 mg. pure 14-methyl-A-nor-5 β - Δ^8 -pregnene-3,20-dione of the following properties: M.P. 178-179°; $[\alpha]_D^{23} +273^\circ$ (c. 0.58 in CHCl_3);

$$\lambda_{\text{max}}^{\text{KBr}} 5.76, 5.87\mu$$

Analysis.—Calcd. for $\text{C}_{21}\text{H}_{30}\text{O}_3$ (314.45): C, 80.21; K, 9.62. Found: C, 80.26; H, 9.59.

Example 13.—14-methyl-21-acetoxy-A-nor- Δ^8 -5 α -pregnene-3,20-dione

432 mg. of 3-isopropylidene-14-methyl-21-acetoxy-A-nor-5 α -pregnene-20-one is ozonized in 40 ml. of methylene chloride and 173 mg. of pyridine as described in Example 12. 1.25 liters of ozone are required and the ozonide is decomposed by the addition of 1 ml. of acetic acid and 1 g. of zinc dust. The amorphous residue is chromatographed on 20 g. of silica gel from a solution of 10 ml. of benzene and 30 ml. of hexane. Elution with benzene and 10% chloroform in benzene produces amorphous material which is followed by a crystalline fraction when the chloroform concentration is raised to 25%. 1500 ml. of that mixture elutes material, which on crystallization from ether-hexane gives 140 mg. of pure material of the following properties: M.P. 99-100°; $[\alpha]_D^{23} +79^\circ$ (c. 0.34 in CHCl_3);

$$\lambda_{\text{max}}^{\text{KBr}} 5.71, 5.76\mu$$

Analysis.—Calcd. for $\text{C}_{25}\text{H}_{32}\text{O}_4$ (372.49): C, 74.16; H, 8.66. Found: C, 74.09; H, 8.72.

Example 14.—14-methyl-A-nor- Δ^8 -5 β -pregnene-21-ol-3,20-dione and 21-acetate

The ozonolysis of 1.4 g. of the isopropylidene derivative is carried out exactly as described in the previous example. The crude residue obtained after the decomposition (1.36 g.) is dissolved in 90 ml. of methanol and treated with 15 ml. of 0.7 N KOH. After 30 minutes at room temperature the mixture is neutralized with glacial acetic acid, diluted with water and concentrated in vacuo. The mixture is extracted with chloroform and the residue from the chloroform extract (1.083 g.) recrystallized from methanol. There is obtained 195 mg. of the pure 21-ol possessing the following properties: M.P. 169-170°; $[\alpha]_D^{23} +242^\circ$ (c. 0.53 in CHCl_3);

$$\lambda_{\text{max}}^{\text{KBr}} 2.90, 5.76, 5.86\mu$$

Analysis.—Calcd. for $\text{C}_{21}\text{H}_{30}\text{O}_3$ (330.45): C, 76.32; H, 9.15. Found: C, 76.33; H, 9.21.

The mother liquor from the above crystallization is evaporated to dryness in vacuo and acetylated with 5 ml. of pyridine and 2 ml. of acetic anhydride for four hours. The reagents are removed in vacuo and the residue crystallized from methanol. 300 mg. of the 21-acetate is obtained possessing the following properties: M.P. 194-195°; $[\alpha]_D^{23} +238^\circ$ (c. 1.34 in CHCl_3);

$$\lambda_{\text{max}}^{\text{KBr}} 5.70, 5.77\mu$$

Analysis.—Calcd. for $\text{C}_{23}\text{H}_{32}\text{O}_4$ (372.49): C, 74.16; H, 8.66. Found: C, 74.18; H, 8.70.

Similarly, treating the 3-isopropylidene-14-methyl-A-nor- Δ^8 -derivatives which may be obtained in accordance with the procedures of Example 7 according to the procedures set forth in Example 11 there is obtained the respective 3-keto-14-methyl-A-nor- Δ^8 -derivatives thereof.

Example 15.—Methyl 5 α -bromo-14-methyl-A-nor- Δ^7 -ergostene-3-one-21-oate

To a solution of 400 mg. of methyl 14-methyl-A-nor-5 α -ergostene-3-one-21-oate in 28 ml. of glacial acetic acid is added at room temperature 0.5 ml. of 6% hydrogen bromide in acetic acid followed immediately thereafter by dropwise addition of 5.15 ml. of a 0.185 molar bromine-sodium acetate solution. After 1.5 hours, the mixture is diluted with water, extracted with chloroform and the chloroform extract washed with water, dilute sodium bicarbonate and again with water, dried over sodium sulfate and evaporated to dryness in vacuo at a bath temperature not exceeding 30°. The resulting residue (503 mg.) on crystallization from methanol yields 146 mg. of methyl 5 α -bromo-14-methyl-A-nor- Δ^7 -ergostene-3-one-21-oate, which after recrystallization has the following properties: M.P. 180° (dec.), $[\alpha]_D^{23} +43^\circ$ (c. 1.66 in CHCl_3),

$$\lambda_{\text{max}}^{\text{KBr}} 5.70, 5.77\mu$$

Analysis.—Calcd. for $\text{C}_{29}\text{H}_{45}\text{O}_3\text{Br}$ (520): C, 66.97; H, 8.72; Br, 15.3. Found: C, 66.95; H, 8.28; Br, 15.6.

Similarly, if the 3-keto-14-methyl-A-nor- Δ^7 -derivatives which may be obtained in accordance with the procedures set forth in Example 10 are treated according to the procedure of Example 15, the respective 3-keto-5 α -bromo-14-methyl-A-nor- Δ^7 -derivatives thereof are obtained.

Example 16.—Methyl-5 β -bromo-14-methyl-A-nor- Δ^7 -ergostene-3-one-21-oate

The mother liquor obtained in Example 15 is concentrated to yield 35 mg. of methyl-5 β -bromo-14-methyl-A-nor- Δ^7 -ergostene-3-one-21-oate, which on recrystallization from ethanol has the following properties: M.P. 105°; $[\alpha]_D^{23} +9^\circ$ (CHCl_3).

Analysis.—Calcd. for $\text{C}_{29}\text{H}_{45}\text{O}_3\text{Br}$ (520): C, 66.97; H, 8.72. Found: C, 66.95; H, 8.80.

Similarly, treating the 3-keto-14-methyl-A-nor- Δ^7 -derivatives obtained in Example 10 in accordance with the

procedures of Examples 15 and 16, there is obtained the 3-keto-5 β -bromo-14-methyl-A-nor- Δ^7 -derivatives thereof.

Example 17.—Methyl-5 α -bromo-14-methyl-A-nor- Δ^8 -ergostene-3-one-21-oate

A solution of 20 mg. of methyl 14-methyl-A-nor- Δ^8 -5 α -ergostene-3-one-21-oate in 2 ml. of glacial acetic acid is brominated with 0.260 ml. of 0.185 Br₂M and sodium acetate in acetic acid as described in Example 15. Methyl 5 α -bromo-14-methyl-A-nor- Δ^8 -ergostene-3-one-21-oate is recrystallized from methanol and has the following properties: M.P. 143–144° (dec.), $[\alpha]_D^{23} +60^\circ$ (c. 0.28 in CHCl₃),

$$\lambda_{\text{max}}^{\text{KBr}} 5.70 \text{ (shoulder)} 5.77\mu$$

Analysis.—Calcd. for C₂₉H₄₅O₃Br (520): C, 66.97; H, 8.72. Found: C, 66.96; H, 8.78.

Similarly, if the 3-keto-14-methyl-A-nor- Δ^8 -derivatives which may be obtained in accordance with the procedures of Example 15 are treated in accordance with the procedures set forth in Example 17, the 3-keto-5 α -bromo-A-nor- Δ^8 -derivatives thereof are obtained.

Example 18.—Methyl 14-methyl-A-nor- $\Delta^5(10),6,8$ -ergostatriene-3-one-21-oate

A solution of 100 mg. of methyl 5 α -bromo-14-methyl-A-nor- Δ^7 -ergostene-3-one-21-oate and 1.0 g. of lithium bromide in 10 ml. of dimethyl formamide are heated on the steam bath for 2 hours. The mixture is then diluted with water, extracted with chloroform, the chloroform extract washed with water, dried over sodium sulfate and evaporated to dryness in vacuo. Crystallization of the residue from methanol yields the pure methyl 14-methyl-A-nor- $\Delta^5(10),6,8$ -ergostatriene-3-one-21-oate of the following properties: M.P. 137–138°; $[\alpha]_D^{23} +11^\circ$ (c. 1.0 in CHCl₃),

$\lambda_{\text{max}}^{\text{alc.}} 217 \text{ m}\mu$ (20,000), 261 m μ (10,400), 295 m μ (2000, plateau); $\lambda_{\text{max}}^{\text{KBr}} 5.78, 5.85, 6.29\mu$

NMR.: protons at C₆ and C₇: doublets centered at 2.45 and 2.94 τ . J=8 cps. 14-methyl at 8.92.

Analysis.—Calcd. for C₂₈H₄₄O₃ (424.60): C, 79.20; H, 9.50. Found: C, 79.24; H, 9.48.

Similarly, treatment of the 3-keto-5 α -bromo-14-methyl-A-nor- Δ^7 -derivatives, which are obtained according to the procedures set forth in Example 15, in accordance with the procedures of Example 18 yields the respective 3-keto-14-methyl-A-nor- $\Delta^5(10),6,8$ -triene derivatives thereof.

Example 19.—Methyl 14-methyl-A-nor- $\Delta^5(10),6,8$ -ergostriene-3-one-21-oate

Following the procedure set forth in Example 18, but substituting equivalent amounts of methyl-5 β -bromo-14-methyl-A-nor- Δ^7 -ergostene-3-one-21-oate and methyl 5 α -bromo-14-methyl-A-nor- Δ^8 -ergostene-3-one-21-oate for methyl-5 β -bromo-14-methyl-A-nor- Δ^7 -ergostene-3-one-21-oate, there is obtained methyl-14-methyl-A-nor- $\Delta^5(10),6,8$ -ergostriene-3-one-21-oate.

Similarly, if the 3-keto-5 β -bromo-14-methyl-A-nor- Δ^7 -derivatives, obtained in accordance with Example 16, and the 3-keto-5 α -bromo-14-methyl-A-nor- Δ^8 -derivatives, obtained in accordance with Example 17, are treated in accordance with the procedures set forth in Example 18, the respective 3-keto-14-methyl-A-nor- $\Delta^5(10),6,8$ -triene derivatives thereof are obtained.

Example 20.—Methyl-14-methyl-A-nor- $\Delta^5(10),6,8$ -ergostriene-20-one-21-oate

A solution of 30 mg. of methyl 5 α -bromo-14-methyl-A-nor- Δ^7 -ergostene-3-one-21-oate in 6 ml. of collidine is refluxed for 2 hours under a blanket of nitrogen. The solution is cooled, diluted with benzene and extracted twice with ice cold 6 N HCl sodium bicarbonate and finally with water. The benzene extract is dried over sodium sulfate and evaporated to dryness in vacuo. The residual oil (24 mg.) crystallizes from methanol and gives

10 mg. of methyl-14-methyl-A-nor- $\Delta^5(10),6,8$ -ergostriene-20-one-21-oate, crystals melting at 135–137°. Preparative thin layer chromatography on activity V alumina gives an additional 4 mg. of material. One recrystallization raises the melting point to 137–138°.

Example 21.—Methyl 14-methyl-A-nor- $\Delta^5(10),6,8$ -ergostriene-21-oate

A suspension of 10 mg. of 10% Pd catalyst on carbon in 5 ml. of 95% alcohol is prerduced with hydrogen (uptake 0.77 ml. in 15 minutes). To this suspension is added 10 mg. of methyl 14-methyl-A-nor- $\Delta^5(10),6,8$ -ergostriene-3-one-21-oate and the hydrogenation continued. Hydrogen uptake ceases after 10 minutes when 1.08 ml. has been absorbed. The mixture is filtered, evaporated to dryness and the residue recrystallized from methanol. There is obtained 9 mg. of the pure methyl 14-methyl-A-nor- $\Delta^5(10),6,8$ -ergostriene-21-oate possessing the following properties: M.P. 88–89° with resolidification and remelting at 101–102°; $[\alpha]_D^{23} +6.4^\circ$ (c. 0.2 in CHCl₃);

$$\lambda_{\text{max}}^{\text{KBr}} 5.78\mu; \lambda_{\text{max}}^{\text{alc.}} 268 \text{ m}\mu (820), 273 \text{ m}\mu (690), 278 \text{ m}\mu (820)$$

NMR.: Protons at C₆ and C₇: doublets centered at 2.97 and 3.18 τ , J=8 cps. 14-methyl at 9.83 τ .

Analysis.—Calcd. for C₂₈H₄₂O₂ (410.62): C, 81.90; H, 10.31. Found: C, 81.80; H, 10.29.

Similarly, treating the 3-keto-14-methyl-A-nor- $\Delta^5(10),6,8$ -triene derivatives obtained in Example 18 in accordance with the procedures set forth in Example 21 yields the respective 14-methyl-A-nor- $\Delta^5(10),6,8$ -triene derivatives thereof. When the pregnene derivatives of this invention are treated in accordance with the procedures of Example 21, the 20-keto group has also been reduced to yield a 20-ol compound. Reoxidation of this compound, as by the well-known treatment with chromium trioxide yields the 20-keto A-nor-pregnatriene derivative of Example 21.

Example 22.—Methyl 14-methyl-A-nor- $\Delta^5(10),6,8$ -ergostriene-3-ol-21-oate

To an ice-cold solution of 10 mg. of the methyl 14-methyl-A-nor- $\Delta^5(10),6,8$ -ergostriene-3-one-21-oate in 5 ml. of methanol is added 10 mg. of sodium borohydride. The mixture is allowed to warm up to room temperature and run for a total of two hours. Water and chloroform are added, the chloroform extract washed with water, dried over sodium sulfate and evaporated to dryness in vacuo. The residue represents methyl 14-methyl-A-nor- $\Delta^5(10),6,8$ -ergostriene-3-ol-21-oate,

$$\lambda_{\text{max}}^{\text{alc.}} 267 \text{ m}\mu (810), 276 \text{ m}\mu (620)$$

Similarly, treating the 3-keto-14-methyl-A-nor- $\Delta^5(10),6,8$ -triene derivatives obtained in Example 18 in accordance with the procedures set forth in Example 22 yields the 3-hydroxy-14-methyl-A-nor- $\Delta^5(10),6,8$ -triene derivatives thereof.

Example 23.—Methyl 3-acetoxy-14-methyl-A-nor- $\Delta^5(10),6,8$ -ergostriene-21-oate

A solution of 25 mg. of methyl 14-methyl-A-nor- $\Delta^5(10),6,8$ -ergostriene-3-ol-21-oate in 1 ml. of pyridine and 0.5 ml. of acetic anhydride is allowed to stand overnight at room temperature. The reagents are removed in vacuo and the residue, consisting of methyl 3-acetoxy-14-methyl-A-nor- $\Delta^5(10),6,8$ -ergostriene-21-oate, is recrystallized from methanol.

Similarly, treating the 3-hydroxy-14-methyl-A-nor- $\Delta^5(10),6,8$ -triene derivatives obtained in Example 15 according to the procedures of Example 16 yields the respective 3-acetoxy-14-methyl-A-nor- $\Delta^5(10),6,8$ -triene derivatives thereof.

Example 24.—Methyl 3-acetoxy-14-methyl-A-nor- $\Delta^5(10),6,8$ -lanostriene-21-oate

Following the procedures set forth in Examples 7, 11, 17, 18, 19, 20, 21, 22 and 23 but employing methyl

11

acetyl- Δ^8 -lanostene-3 β -ol-21-oate yields methyl 3-acetoxy-14-methyl-A-nor- $\Delta^{5(10),6,8}$ -lanostatriene-21-oate.

Like results are obtained when methyl acetyl- Δ^7 -lanostene-3 β -ol-21-oate is substituted for methyl acetyl- Δ^8 -lanostene-3 β -ol-21-oate.

The invention may be variously otherwise embodied within the scope of the appended claims.

What is claimed is:

1. A compound of the formula

wherein R is hydrogen; R'' is selected from the group consisting of hydrogen, hydroxy and the acyloxy radical of a hydrocarbon carboxylic acid of less than ten carbon atoms and together R and R'' is oxo; R' is selected from the group consisting of hydrogen and the acyloxy radical of a hydrocarbon carboxylic acid of less than ten carbon atoms; and Z is selected from the group consisting of

wherein Y is iso-alkyl and X is selected from the group consisting of lower alkyl and

wherein B is selected from the group consisting of hydroxy and lower alkoxy; and

wherein W is selected from the group consisting of hydrogen, the acyloxy radical of a hydrocarbon carboxylic acid of less than ten carbon atoms and halogen.

2. A compound selected from the group consisting of steroid derivatives of the formulae

wherein Q is selected from the group consisting of hydrogen and bromine and Z and R' are as defined in claim 1.

3. A compound selected from the group of steroid derivatives of the formulae

and

5

10

25

30 and

35

40

45

50

60

65

70

wherein W is selected from the group consisting of hydrogen, the acyloxy radical of a hydrocarbon carboxylic acid of less than ten carbon atoms and halogen; and R' is as defined in claim 1.

4. A compound selected from the group of steroid derivatives of the formulae

wherein X is selected from the group consisting of lower alkyl and

wherein B is selected from the group consisting of hydroxy and lower alkoxy; Y is iso-alkyl; and R' is as defined in claim 1.

5. Methyl 3-isopropylidene-14-methyl-A-nor- Δ^7 -5 α -ergostene-21-oate.

6. Methyl 3-isopropylidene-14-methyl-A-nor- Δ^8 -5 α -ergostene-21-oate.

7. Methyl 14-methyl-A-nor- Δ^7 -5 α -ergostene-3-one-21-oate.

8. Methyl 14-methyl-A-nor- Δ^8 -5 α -ergostene-3-one-21-oate.

9. Methyl 5 α -bromo-14-methyl-A-nor- Δ^7 -ergostene-3-one-21-oate.

10. Methyl 14-methyl-A-nor- $\Delta^{5(10),6,8}$ -ergostatriene-3-one-21-oate.

11. Methyl 14-methyl-A-nor- $\Delta^{5(10),6,8}$ -ergostatriene-21-oate.

12. Methyl 14-methyl-A-nor- $\Delta^{5(10),6,8}$ -ergostatriene-3-ol-21-oate.

13. 14-methyl-A-nor- Δ^8 -pregnene-3,20-dione.

14. 14-methyl-A-nor- Δ^8 -5 β -pregnene-21-ol-3,20-dione 21-acetate.

15. 3-isopropylidene-14-methyl-A-nor- Δ^8 -5 α -pregnene-20-one.

16. Isopropylidene-14-methyl-A-nor- Δ^8 -5 α -pregnene-21-ol-20-one.
